UNITED STATES PATENT OFFICE.

WALTON HARRISON, OF BROOKLYN, NEW YORK

RECEIVER FOR WIRELESS COMMUNICATION.

1,097,974.

Specification of Letters Patent. Patented May 26, 1914.

Application filed August 27, 1903. Serial No. 170,945.

To all whom it may concern:

Be it known that I, WALTON HARRISON, a citizen of the United States, residing at Brooklyn, New York, have invented certain new and useful Improvements in Receivers for Wireless Communication, of which the following is a specification:

My invention relates to wireless communication, my more particular object being to produce a system in which the responsive effect of a number of separate antennæ and separate wave detectors is rendered cumulative and thereby made more distinct, and is also rendered less irregular.

15 In the accompanying drawing forming a part of this specification, in which like letters indicate like parts, the figure represents a diagrammatic front elevation of the preferred form of my system, showing a number of separate antennæ exposed to wave action, and used with a number of wave detectors connected in parallel with each other with reference to the local circuit, and in series with the receiving instrument.

25 A number of antennæ 4, preferably vertical as shown, are spaced apart and provided with aerial plates 5, self-restoring coherers 6 or equivalent devices sensitive to electro magnetic waves, and separate ground terminals 7. An ordinary telephone receiver 8 is connected in series with a battery 22, which is grounded by a wire 23. The coherers 6 are, by means of fine iron wires 24, 26, connected in parallel with each other with reference to the coherers 6. The several antennæ 4 are disposed in a row crossing the general path of wave propagation, and being spaced apart and completely disconnected from each other except in relation to the 40 battery circuit, are thus exposed independently of each other, to the action of the waves. A number of coils 25, provided with laminated iron cores 27 are employed to prevent the oscillations in the antennæ from flowing horizontally. The material (iron) of the wire 26 and the fineness of this wire also contribute to this end. The portions of the wire 26, spanning the spaces intermediate of the antennæ, thus constitute bridges

45 which permit the battery current to pass freely, but prevent the flow of surges from one antenna to another, along the metallic path representing the battery circuit.

The several antennæ are "in resonance" 55 with each other. To this end, they have the same inductance, capacity and ohmic resistance, and equal oscillation periods. The

antennæ are disposed in a row crossing at a right angle the general direction of propagation of the electro magnetic waves. The 60 idea is, to so distribute the antennæ as to intercept a considerable wave-section and also to render substantially equi-potential the several junctions between the bridges and antennæ. 65

I do not limit myself, however, to any particular form of apparatus, the scope of my invention being commensurate with my claims.

The sending apparatus may be of the usual or any approved construction.

The action of the apparatus is as follows: The electro-magnetic waves, emanating from the transmitting station, strike abreast the row of receiving antennæ as above described. 75

Oscillations having a common period are set up simultaneously in the several antennæ, each coherer is individually affected, and its resistance thereby diminished, as in ordinary wireless communication. There 80

fore, the battery current splitting and passing in parallel through several coherers is varied in power in accordance with Ohm's law $C = \frac{E}{R}$. As the current employed in the 85

battery circuit is substantially commensurate with the number of coherers, and as the variations in the ohmic resistances of the battery circuit represent substantially the 90

sum of the separate variations in ohmic resistances of the several coherers, it follows that while the number of millamperes passing through each coherer is not increased, the variations in the current passing through the receiver 8 are nevertheless exaggerated 95 in proportion to the number of antennæ and coherers. The sounds produced by the receiver are therefore louder and clearer, and the sensitiveness of the apparatus greatly increased. 100

The circuit is as follows: Battery 22, wire 21, receiver 8, wire bridges 26, thence in parallel through the coherers 6 and portions of the antennæ 4 to the earth, thence through ground wire back to the battery. The battery current is thus divided, so that each coherer allows its pro rata proportion of energy to pass through it, yet the variation in the current through telephonic receiver is equal to the sum of the variations in the currents through the several coherers, in accordance with Ohm's law, $C = \frac{E}{R}$. By this arrangement the receiver 8 is affected by cur-

rent variations, the power of which is commensurate with the number of coherers. The sounds made by the transmitter are therefore greatly improved, because a current of 5 greater amperage is brought under better control of the co-acting wave detectors.

In this system a distinct advantage of another kind is gained, to wit: the uncertainty attending the use of a single detector 10 is greatly lessened. Practically all wave detectors heretofore used work irregularly, and at times cease to respond at all to the waves. By the system above described the general effect of several detectors is merged, 15 and therefore "averaged", so if at a particular moment some of the detectors work badly, others of them work better than usual, and thus the aggregate effect is rendered comparatively reliable and constant. 20 While the preferred form of wave detector used with my invention may consist of an antenna in connection with a coherer, it is obvious that other wave detectors may be employed without departing from the spirit 25 of my invention. I prefer to employ oscillations, and especially the kind produced by Hertzian waves, but do not limit myself to the use of the same in instances where other electrical disturbances may be employed. 30 Neither do I limit myself to the particular wiring shown, the scope of my invention being commensurate with my claims.

What I claim as new and desire to secure by Letters Patent is:

35 1. In a receiver system for wireless communication, the combination of a plurality of antennæ grounded separately and having equal oscillation periods, a separate wave detector for each antenna, and a local circuit connected with all of the wave detectors.

2. In a receiver system for wireless communication, the combination of a plurality of antennæ having equal oscillation periods and energized independently, a local circuit 45 and a number of separate wave detectors in electrical communication with said antennæ, and connected in parallel with each other with reference to said local circuit.

3. In a receiver system for wireless communication, the combination of a plurality of antennæ grounded separately and having equal oscillation periods, said antennæ being disposed in a row crossing the general path of wave propagation, and means for 55 cumulating the effects of the wave energy received by all of said antennæ.

4. The combination of a plurality of antennæ, more than two in number, spaced widely apart and grounded separately, and 60 means for adding the effects of the wave energy received by all of said antennæ.

5. The combination of a plurality of an-

tennae, more than two in number, spaced widely apart in a direction crossing the path of wave propagation and grounded separately, and means for totalizing, in arithmetical ratio to the number of antennæ the energy received by the same. 65

6. The combination of a plurality of aerials, more than two in number, grounded separately and spaced apart in a direction crossing the path of wave propagation, said aerials being proportioned for time periods of equal length, and means including an oscillation detector associated with all of 75 said aerials and receiving from each aerial its proportionate part of the entire aggregate energy controlling said oscillation detector. 80

7. In a system for wireless communication, the combination of a plurality of antennæ, more than two in number, each antenna having a separate ground, the several grounds being disposed across the path of wave propagation, and means including 85 an oscillation detector for adding the effects of the wave energy received by all of said antennæ.

8. In a receiver system for wireless communication, the combination of a plurality of antennæ more than two in number, spaced widely apart so that each is energized to its maximum capacity as if segregated, said antennæ being grounded separately, and a local circuit for totalizing, in 95 arithmetical ratio to the number of antennæ, the energy received by the same. 90

9. In a receiver system for wireless communication the combination of an indicating mechanism, a local circuit connected 100 with said indicating mechanism for energizing the same, a plurality of separate antennæ grounded separately and spaced apart in order to enable each antenna to be energized to its maximum capacity as if 105 segregated, and a plurality of separate members included in said local circuit and severally energized by aid of said antennæ for the purpose of controlling said local circuit. 110

10. In a receiver system for wireless communication the combination of a plurality of separate antennæ spaced apart and grounded separately, an oscillation detector for each antenna, and a local circuit connected with all of said oscillation detectors 115 and controllable thereby.

In testimony whereof, I have signed my name to this specification in the presence of two subscribing witnesses, this 24th day of August, 1903.

WALTON HARRISON.
